UNITED STATES PATENT OFFICE.

CHARLES J. LIPPOLD, OF WASHINGTON, DISTRICT OF COLUMBIA.

STRING FASTENER.

Application filed October 11, 1924. Serial No. 743,089.

This invention relates to string fasteners, and especially to an improved form of wire fastener for use in securing a string around a package.

One object of this invention is to provide an exceedingly strong and effective fastener of this character which is exceedingly simple in form, and capable of being produced at an exceedingly low cost.

Another object is to provide a device of this character which is exceedingly convenient in the operation of fastening the string, and which holds the string with the maximum security.

Other objects and important features are pointed out or implied in the following details of description, in connection with the accompanying drawing in which:

Figure 1 is a plan view of the device in its useful position, that is, in connection with a string around a package secured thereby.

Fig. 2 is a plan view of the wire fastener detached from the string and package; and,

Fig. 3 is an edge view of the device shown in Fig. 2.

Referring to these drawings in detail, in which similar reference characters correspond to similar parts throughout the several views, and in which the package P is shown for illustrating the use of the invention:

The wire element is formed of a single length of wire and includes two substantially straight and parallel sections 5 and 6, the end of the section 6 being extended to form a loop 7 into which the end of the section 5 extends and is embraced between the section 6 and the other end of the wire which is indicated at 8. The loop 7 includes an opening 9 which is substantially of the same length and breadth, that is, substantially the same distance across the sections 6 and 8 as the distance from the end of the section 5 to the opposite side of the opening 9. Therefore, when this opening 9 is substantially filled with a string which is passed therethrough, a knot 10 of the string cannot pass therethrough, and the string cannot pass laterally from the opening 9, in consequence of the wire section 5 closing the loop. This form of string fastening not only accomplishes the results hereinbefore specified, but also serves to secure the parts 5 and 6 in fixed relation to one another, it being understood that the parts 6 and 8 may either exert

a clamping effect on the part 5, or that they may be secured in fixed relation by means of solder, lacquer or other cementing liquid into which they may be dipped for giving them any desired finishing coat.

At the opposite end of the device, from the loop 7, is formed a horse-shoe-shaped loop 11 which has its main bight portion 12 overlying and spaced from the intermediate parts of the sections 5 and 6. The lesser bight portions 13 are substantially in the same plane with the sections 5 and 6, and, therefore, when the string or wrapping twine is passed through these bight portions, as shown in Figure 1, such string is bent upward at a and downward at b each time it is passed around these bight portions 13, and moreover, the parts a and b overlie and bear upon the part c, thus exerting a wedging effect and a frictional engagement which effectively prevents the string from loosening upon the package tied thereby.

Referring to Figures 1 and 3, it will be understood that the parts a, b and c of the string are passed through an opening 14 under the bight portion 12, the part c being first to engage with the bight portions 13, and then, after extending the part c around the package, the parts a—b are passed through the opening 14, forced over the part c, and held taut while the part d is moved in the direction of the arrow until it also passes into the opening 14 and over the part c. By continuing this operation several times, the fastening becomes increasingly secure, and the security thereof may be perfected by passing the end of part b through the loop 11, towards the part 8, and then drawing it around towards the arrow head until it crosses the parts a and f.

From the foregoing, it will be seen that I have provided a device of this character having the important features specified, and eliminating the objectionable features of becoming easily entangled with other devices of its kind when a number of them are kept in bulk for use as occasion requires.

It is not intended to limit my patent protection to the exact form here shown and described, for changes may be made within the scope of the inventive ideas, as implied and claimed.

What I claim as my invention is:

1. In a device of the character described, a length of wire including two substantially straight and parallel sections, a horse-shoe-

shaped loop at one end of said sections and having its main bight portion overlying and spaced from these sections, a string-attaching loop formed on one of said sections and embracing the other of said sections, the said straight and parallel sections lying against one another, the end of one of these sections terminating a distance from the end of the loop formed by the end of the other of said sections, thus providing an opening through which a string can be passed longitudinally, and from which the string cannot pass laterally.

2. In a device of the character described, a length of wire including two substantially straight and parallel sections, a horse-shoe-shaped loop at one end of said sections and having its main bight portion overlying and spaced from these sections, a string-attaching loop formed on one of said sections and embracing the other of said sections, the said

horse-shoe-shaped loop including bight portions at opposite sides of said parallel sections and substantially in the same plane therewith.

3. In a device of the character described, a length of wire including two substantially straight and parallel sections, a horse-shoe-shaped loop formed of the intermediate part of the wire and united with one end of said sections and having its main bight portion overlying and spaced from the intermediate parts of said straight sections, one of these sections being longer than the other and forming a string-securing loop of one end portion of said length of wire, the shorter one of said sections including the other end portion of said length of wire, these end portions adjoining one another at one side of the longer one of said straight sections.

In testimony whereof I affix my signature.

CHARLES J. LIPPOLD.
